UNITED STATES PATENT OFFICE.

FRANK FURLONG, OF JERSEY CITY, NEW JERSEY.

SHIP-LAUNCHING DEVICE.

Application filed June 4, 1921. Serial No. 475,033.

To all whom it may concern:

Be it known that I, FRANK FURLONG, citizen of the United States, and resident of Jersey City, in the county of Hudson and State of New Jersey, have invented certain new and useful Improvements in Ship-Launching Devices, of which the following is a specification.

This invention relates to a ship launching device.

The object of the invention is the production of such a device whereby the weight of the ship is taken off the keel blocks during the launching and avoids injury to said blocks, as the ship slides down into the water. A further object of the invention is to prevent the expensive and tedious method of inserting wedges in the blocking that supports the sides of the ship previous to its launching.

The organization of the invention comprises essentially a pair of standing timbers that are slidably supported on roller bearing plates, which in turn are supported on a series of rollers which are located adjacent to each other and vary in diameter from one end of the series to the other. The rollers are supported on inclined bearing faces of roller bearing casings.

Sliding timbers which support the ship or other object to be launched are slidably supported on the standing timbers. Means are provided to longitudinally move the standing timbers, and while moving in one direction are slightly raised by reason of the rollers rolling from one end of their casings to the other. The sliding timbers with the ship are raised with the elevations of the standing timbers. The sliding timbers are then released and they, with their load, slide down the standing timbers and runway timbers extending therefrom into the water.

The drawings represent one exemplification of the invention.

Fig. 1 represents a side elevation of the ship launching device with portions thereof broken away with a ship in place; Fig. 2 shows a partial top plan view of Fig. 1; Fig. 3 indicates an enlarged fragmentary portion of Fig. 1 with some details in section as on the line 3, 3 of Fig. 4; Fig. 4 shows a top plan view of Fig. 3 with some of the parts broken away and omitted; Fig. 5 represents an enlarged section of Fig. 1

on the line 5, 5; Fig. 6 shows an enlarged side elevation of some details; Fig. 7 represents a top plan view of Fig. 6 and Fig. 8 shows an enlarged fragmentary portion of Fig. 6, and Fig. 9 indicates a fragmentary portion of Fig. 6 with some of the elements in a different position.

Piles are indicated at 20 and have secured thereto the cross timbers 21 for the inclined flooring 22. Longitudinal stringers 26 are secured to the flooring 22 and have in turn fastened thereto the blocks 27, that support the usual wedges 28, 29 for the keel blocks 30. Two rows of supporting blocks 32 with tapered notches 34 in their upper faces 35 are secured to the flooring 22. Cross planks 39 connect the opposite pairs of blocks 32. Metallic roller bearing casings 40 are supported in the notches 34. Each casing 40 comprises the inclined bottom wall 41 with the straight edge 42 at one end and the flange 43 with the top edge 44 at its other end. The edges 42 and 44 are in line with the upper face 35 of its block 32. A series of rollers indicated at 45 to 52 are located in each casing 40. The smallest roller is shown at 45 and the largest roller at 52. The diameters of said rollers gradually increase from 45 to 52 and their cylindrical surfaces slightly extend above the plane of the edges 42 and 44 of the casing 40. A roller bearing plate 53 is supported on said rollers.

Stationary tapering supporting timbers 60 longitudinally in line with the supporting blocks 32 are fastened to the flooring 22. A runway timber 61 with the upper abutting end 62 and the tapered upper end face 63 is fastened to each of the supporting timbers 60. A standing timber designated in its entirety by the letter A and having ends 64 and 65, the upper face 66 and the lower face 67 comprises three timbers connected together and slidably located above each of the rows of supporting blocks 32. The lower face 67 of each standing timber A is supported upon the roller bearing plates 53. A guide plank 68 is fastened to the outer face of each standing timber A and an abutting rail 69 is fastened to each guide plank 68. Linked chains 70 are located on the outer faces of the standing timbers A and on the outer faces of the guide planks 68. The upper ends of the chains 70 are shown with the links 71 and the lower ends of the chains

70 have connected thereto the U shaped links 73 that bear against the ends 65 of the standing timbers A. A wedge shaped apron 74 has its larger end loosely connected to the 5 standing timber A adjacent to its end 65 by means of screws, the heads 75 and shanks of which are somewhat smaller in diameter than the openings therefor in said wedge. The other portion of the wedge bears on the 10 tapered upper end face 63 of the runway timber 61. Posts 76 with the tables 77 and upper portions 78 are fastened to the flooring 22 adjacent to the outer faces of the blocks 32 and may also be located adjacent 15 to the outer faces of the timbers 60. Longitudinal rails 82 connect the posts 76 and braces 83 connect the upper portions 78 and the flooring 22. The upper portions 78 abut against the abutting rails 69.

20 Upon each standing timber A is slidably supported the sliding timber designated in its entirety by the letter B, and comprises in this instance the rows of three timbers 84 which together are of the same width as the 25 standing timber A. The upper edges of the timbers B are indicated at 85. The timbers 84 are connected by the side links 90 which are pinned to the accompanying ends of said timbers by the pins 91, whereby flexibility 30 is obtained for the sliding timbers B. Wedge shaped blocking 94 and 95 is located upon each of the sliding timbers B. Holding timbers 96 bear against the outer faces of the blocking 94 and lashing 97 connect the 35 holding timbers 96. Between the accompanying faces of the timbers A and B is interposed a viscous lubricant.

40 A housing is indicated in its entirety by the letter C, and comprises the posts 100, 101, cross girders 102, 103, floor timbers 104 and the flooring 105. Longitudinal girders 106 are supported on the cross girders 102 and longitudinal holding timbers 108 are supported on the cross girders 103. A cross 45 timber 111 connects the holding timbers 108. To each of the sliding timbers B are fastened a pair of journal bearing irons 114 and each of said irons is provided with a shackle iron 115. To the sides of each of 50 the holding timbers 108 are secured journal bearing irons 116. A latch shaft 117 is journaled in the journal bearing irons 116 and has extending therefrom the latch hooks 118 and the locking handle 119. In the 55 cross timber 111 is secured a metallic tapered sleeve 120 for the gib 121 with the head 122 and the tapered key 123 having the opening 124 in its head. A ship D is supported upon the keel blocks 30 and the blocking 94 and 95. Posts 128 abut against the girders 106, the holding timbers 108 and the outer girders 102. Each of the links 71 of the linked chains 70 have connected thereto a tackle block E. Each of said blocks 60 comprises the side members 130 which are fas-

tened to its link 71, the latter extending up some distance between said members. Cross bolts 131 and journal bolts 132 connect the said side members 130 and extend through the links 71. Sheaves 133 are journaled on 70 the journal bolts 132. U shaped members 136 extend around each pair of posts 128. Each of the members 136 has connected thereto a tackle block F similar to the tackle blocks E.

75 A pair of pillow blocks 138 is supported upon and fastened to the longitudinal girders 106. A drum shaft 139 is journaled in the pillow blocks 138. A combined spur gear 140, winding drums 141 and ratchet 80 wheels 142 are fastened to the drum shaft 139. Pawls 143 are indicated with the pivots 144. The pivots are supported in the pillow blocks 145 which are fastened to the girders 106 and the pawls 143 engage the teeth of 85 the ratchet wheels 142. Four pillow blocks 147 are supported upon and fastened to girders 106 and have journaled therein the small drum shaft 150. Drums 151 and the pinion 152 are fastened to the shaft 150. 90 The pinion 152 meshes with the spur gear 140.

95 Wire ropes 155 have one end each fastened to the tackle blocks F, wind around the sheaves of the tackle blocks E and F and have their other ends fastened to and wound around the drums 151. Wire ropes 156 have one end each fastened to and wound around the winding drums 141.

100 To use the launching device the keel of the ship is located upon the keel blocks 30, and built in the regular way. The sliding timbers B are located with their top ends 105 close to the adjacent ends of the longitudinal holding timbers 108. The latch hooks 118 of the latch shaft 117 are locked with their coating shackle irons 115. The locking handle 119 is swung to its horizontal position. The gib 121 is located in the sleeve 120 with its head 122 bearing on the 110 end of the handle 119. The key 123 is next locked with said gib. The blocking 94 and 95 is located upon the sliding timbers B to support the ship D. The holding timbers 96 with the lashing 97 is put in place in the 115 usual way. The standing timbers A have their upper ends 64 spaced from the housing C. Power, not shown, is applied to the wire ropes 156, whereby the drums 141, the spur gear 140 and the ratchet wheels 142 are 120 turned in the direction of arrow G. With the rotations of the spur gear 140 the pinion 152 turns in the direction of the arrow H, and the ropes 155 are wound on the drums 151.

125 The tackle blocks E now move toward the tackle blocks F whereby the standing timbers A are moved toward the housing C. While the timbers A are moving toward the housing C the roller bearing plates 53 ride 130

on the rollers 45 to 52 and the latter move from the edges 44 of the flanges 43 toward the edges 42 of the casings 40.

With the movements of rollers in the casings 40 and the consequent movements of the bearing plates 53, the latter rise and raise the standing timber A. By this means the ship D is slightly raised from the keel blocks 30. The said keel blocks and the wedges 28 and 10 29 are now removed intact without injury and the ship is ready for launching.

This is accomplished by withdrawing the key 123 when the locking handle 119 swings up and the latch hooks 118 unlock themselves 15 from the shackle irons 115, and the sliding timbers B with the ship D slide down the standing timbers A. As the standing timbers A are drawn up by the tackle blocks, the aprons 74 fill up the gap between the lower 20 ends 65 of the said standing timbers and the upper ends 62 of the runway timbers 61. After the said ends 65 and 62 are separated from each other, blocks 160 are placed between said ends and under the aprons 74. 25 The blocks 160 constitute safety locking devices for the standing timbers A, and prevent the latter slipping after being pulled up in case of breakage of the chains 70 or any of their connections.

Having described my invention what I desire to secure by Letters Patent and claim is:

1. In a launching device the combination of supporting blocks having inclined upper faces with tapered notches, roller bearing casings, with inclined bottom walls seated in said notches, rollers gradually varying in diameter, one relatively to the other, in each of said casings, bearing plates supported on the rollers, standing timbers supported on 35 the bearing plates and sliding timbers slidably supported on the standing timbers.

2. In a launching device the combination of supporting blocks, having inclined upper faces, standing timbers over said blocks, 45 means to longitudinally move said standing timbers, means to automatically raise said standing timbers while moving longitudinally, sliding timbers slidably supported on the standing timbers and means to lock the 50 sliding timbers in place.

3. In a launching device the combination of supporting blocks having inclined upper faces with tapered notches, rollers gradually varying in diameter, one relatively to 55 the other, in said notches, standing timbers supported on said rollers, sliding timbers slidably supported on the standing timbers and chains for the standing timbers to horizontally move them.

4. In a launching device the combination of supporting blocks having inclined upper faces with tapered notches, roller bearing casings with inclined bottom walls seated in 65 said notches, rollers of various diameters in said casings, said rollers extending slightly

above the upper faces of the supporting blocks, bearing plates supported on said rollers, standing timbers carried on said bearing plates, sliding timbers slidably supported on the standing timbers, chains with 70 their lower ends engaging the lower ends of the standing timbers, means connected to said chains to longitudinally move them and thereby move the standing timbers, the rollers rolling with the movements of the 75 standing timbers and locking means for the sliding timbers,

5. In a launching device the combination of supporting blocks having inclined upper faces with tapered notches, casings with inclined bottom walls seated in the notches, rollers of various diameters in said casings, bearing plates supported on said rollers, standing timbers carried on said bearing plates, sliding timbers slidably 80 supported on the standing timbers, the sliding timbers composed of timbers with their adjacent ends flexibly connected to each other, chains to longitudinally move the standing timbers and locking means for the 85 sliding timbers.

6. In a launching device the combination of stationary supporting blocks having inclined upper faces, standing timbers over 90 said blocks, stationary supporting timbers 95 in line with said supporting blocks with their upper ends abutting against the adjacent ends of the supporting blocks, running timbers fastened to said supporting timbers with their upper ends in line with the upper 100 ends of said supporting timbers, means to longitudinally move the standing timbers, means to automatically raise the standing timbers while moving longitudinally, sliding timbers slidably supported on the standing 105 timbers, means to lock the sliding timbers in place and means to lock the standing timbers in place when in their upper positions.

7. In a launching device the combination of stationary supporting blocks, standing 110 timbers over said blocks, stationary supporting timbers in line with said supporting blocks with their upper ends abutting against the adjacent ends of the supporting blocks, runway timbers fastened to said supporting timbers with their upper ends in line with the upper ends of the supporting timbers, means to longitudinally move the 115 standing timbers, means to automatically raise the standing timbers while moving 120 longitudinally, sliding timbers slidably supported on the standing timbers, means to lock the sliding timbers in place, and blocks located between the standing timbers and the runway timbers when they are separated 125 from each other.

Signed at Jersey City in the county of Hudson and State of New Jersey this 23d day of May A. D. 1921.

FRANK FURLONG.
